UNITED STATES PATENT OFFICE.

HENRY W. PETERS, OF WEST BOXBURY, MASSACHUSETTS.

FINGER RING.

Application filed April 28, 1925. Serial No. 26,499.

This invention relates to finger rings and is designed more especially as an improvement upon the structure disclosed in my Patent 1,570,776, dated January 26, 1926. 5 One of the objects of the invention is to provide a finger ring or other article of jewelry wherein an onyx or other stone can be set without requiring the services of an expert and at a greatly reduced cost, certain ornamental portions of the ring or the like being utilized for holding the stone in its proper position.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed may be made within the scope of what is claimed without departing from the spirit of the invention.

In the accompanying drawings the preferred form of the invention has been 25 shown.

In said drawings,

Figure 1 is a plan view of a portion of a ring embodying the present improvements, a part being broken away.

30 Figure 2 is a section through the shield and box portions of the ring, said section being taken on the line 2-2 Figure 1, to show the pivot of one shield.

Figure 3 is a view similar to Figure 1 35 showing a modified construction, one of the positions of the stone retaining member being indicated by broken lines.

Figure 4 is a section through the box portion of the ring, said section being on the 40 line 4-4 Figure 3.

Figure 5 is a plan view of another form of ring in which the shields or crests are both fixedly mounted.

Figure 6 is a side view thereof.

45 Figure 7 is a section through the box and crests taken on line 7-7 Figure 5.

Referring to the figures by characters of reference, 1 designates a portion of a ring provided with a flat surface 2 on which is 50 soldered or otherwise arranged a box 3 adapted to receive an onyx or other stone. This box is provided with an open outer face indicated at 4 and formed or secured across this open face can be a suitable ornamentation such as a monogram or the like 55 adapted to bridge the box as shown, for ex-

ample, at 5. One of those sides of the box which extend across the ring is open so that the onyx or the like indicated at 6 can be inserted edgewise through the open side of the 60 box into position back of the ornamentation 5 so as to fit snugly within the box. The means employed for holding the stone in the box is preferably in the form of a separate piece applied to the ring in such a 65 way that, when brought to proper position relative to said box, it will engage and retain the stone.

One form of retaining means has been illustrated in Figures 1 and 2. The ring 70 illustrated in said figures is of that type wherein a shield or crest is mounted on the ring at opposite sides of the stone. In the present instance one of these shields, indicated at 7, is soldered to the ring at one side 75 of the box prior to the insertion of the stone so that hard solder can thus be used in assembling the parts. The edge of this shield will extend under a lip 11' projecting from the box. After the stone has been 80 inserted through the open side of the box, another shield 8 is applied to the ring at the opposite side of the box, this shield having an outwardly extending portion 9 which laps the setting as shown in Figure 2. 85 Shield 8 is not secured by solder, however, but is fastened in place preferably by a rivet 10 seated in the ring and shield within openings preferably drilled in these parts before they are finally assembled. The outwardly 90 extending portion 9 can project under a lip 11 projecting laterally from the box and against the box, and consequently, when the shield 8 is secured by means of the single rivet the parts will all be properly positioned relative to each other.

Obviously by constructing a ring as described the stones can be readily placed in position without requiring the services of skilled artisans and a considerable saving in 100 the cost of production results not only from the lower cost of labor but also from the elimination of breakage such as occurs so frequently when onyx or similar stones are held in place by rivets extending through 105 them. The riveted shield enables the stone to be changed at will. By attaching one of the shields with hard solder the same can be properly positioned at the time the parts of the ring are assembled so that a very firm 110 connection will be provided. The rings can be sold to the trade so as to be kept in stock

and any desired stone can be inserted in the box by the jeweler who thereafter places the separate shield 8 in position and attaches it with a rivet. This does not require any particular skill and as the shield 8 bears firmly against the side of the box and the side of the flat portion 2 of the ring there, is no danger of the shield swinging or shifting out of place even though fastened with a single rivet. Thereafter this one rivet can be cut and removed, the shield 8 taken off and a new stone substituted. The shield can then be replaced as before explained.

Under some conditions, it is not desired to use shields at the side of a stone. Where such is the case a structure such as illustrated in Figures 3 and 4 can be employed. In this form of the device a retaining member in the form of an elongated strip 12 can be hingedly connected to the box 3 at one end of the open side thereof. After the stone has been inserted into the box this strip 12 can be swung from its open position indicated by broken lines in Figure 3 to its closed position indicated by full lines in said figure. The retaining strip can be held in closed position by snapping its rounded free end 13 into engagement with a lip 14 formed on the box. Obviously other means may be used for holding this strip in shut position. A structure of this type is particularly advantageous where it is desired to change the stones.

If it is not desired to use a removable stone in the ring the structure illustrated in Figures 5, 6 and 7 can be employed. In

this modified device a shield or crest 15 is attached to the ring at one side of the box 16, hard solder being used because the parts are assembled before the stone is inserted. After the stone has been placed in the box 40 through the open side thereof as heretofore described, another crest or shield 17 can be placed on the ring and attached thereto by a pair of rivets or the like so that the shield will be held firmly in place, will lap the 45 stone, and prevent it from being withdrawn through the open side of the box.

What is claimed is:

The combination with a finger ring or the like, of a setting box permanently connected 50 to the ring having opposed open sides one of which is adapted to receive a stone insertable into the setting box, said setting box having an open face through which the stone is exposed, an ornamental plate permanently 55 connected to the ring by hard solder, a stone within the setting box held against displacement in one direction by said plate, a second ornamental plate mounted on the ring for engaging the stone at the other open side 60 of the setting box, the two plates cooperating to hold the stone in the setting box, and means extending into the ring and the last named plate at a point beyond one side of the setting box for holding the plate and 65 ring against relative movement.

In testimony that I claim the foregoing as my own, I have hereto affixed my signature.

HENRY W. PETERS.
